SYSTEM OF TRANSMISSION

Henry M. Vanderhider, San Antonio, Tex.

Application April 28, 1937, Serial No. 139,605

12 Claims. (Cl. 177—351)

This invention relates to systems for the transmission of intelligence and particularly to methods of and apparatus for transmitting and receiving at regular intervals the readings of one or more instruments.

In its preferred form the invention is primarily intended for radio transmission of the readings of meteorological and other scientific and engineering instruments to a distance and the registering and/or recording of these readings in various ways at definite or regular intervals. The invention is, of course, not limited in accordance with the preferred embodiment, for other forms of impulse transmitters other than radio may be resorted to, the apparatus may be used for the transmission of signals as set up by a key board or otherwise, rather than as taken from the registering apparatus of an instrument, and various modifications may be made of the methods and apparatus herein described.

It is a general object of the present invention to provide novel systems and methods of and apparatus for signal transmission and reception.

More particularly it is an object of the invention to provide a telemetric system wherein a plurality of types of receiving devices are each adapted for use with one or more types of transmitting devices and where improved methods of synchronizing the apparatus at two or more stations is provided.

An important feature of the invention resides in the provision of transmitting apparatus capable of sending records of instrument readings by the use of a single impulse for each digit or character in the reading.

Another important feature of the invention resides in improved synchronizing means for maintaining the transmission and receiving equipment in phase at all times to insure accurate results.

A further important feature of the invention consists in the provision of a printing type-wheel provided with a row of digits for each printing impulse sent by the transmitter, together with means to select the row to be printed in accordance with the order of the impulse.

Another important feature of the invention resides in the provision of receiving mechanism adapted to print with typewriter mechanism the readings of instruments as sent from a transmitter, where one impulse is sufficient to actuate each key so that no code need be resorted to for the operation of the system.

Still another feature of the invention resides in the provision of a novel chart recording de-

vice for use with the above system and transmitter.

Further features of the invention consist in the novel correlation of the transmitter, signal conducting system and receiver, whereby accurate results are obtained at all times and the information desired is given visually or in printed form, as letters or other characters or as a charted curve.

Other and further features and objects of the invention both as to method and apparatus will be more apparent to those skilled in the art upon a consideration of the accompanying drawings and following specification wherein are disclosed several exemplary embodiments of method and apparatus, types of transmitters being illustrated adapting for use with several types of receivers and receiving apparatus being shown available for use with various of the types of transmitters, it being understood that such combinations and modifications may be made in the apparatus and systems as fall within the scope of the appended claims without departing from the spirit of the invention.

In said drawings:

Figure 1 is a diagrammatic showing of apparatus for transmitting the reading of a single instrument;

Figure 2 is a diagrammatic and schematic showing of apparatus for receiving and printing a record of the reading of an instrument, transmitted for instance by apparatus such as shown in Figure 1;

Figure 3 is a front elevation of the printing wheel and associated equipment of Figure 2;

Figure 4 is a side elevation, partly in section, of apparatus for feeding and printing on a timed tape for use with the equipment of Figure 2;

Figure 5 is a perspective view of a contact arm and contact brush thereon;

Figure 6 is a schematic showing of synchronizing apparatus of the mechanical type;

Figure 7 is a view similar to Figure 1 showing a transmitting arrangement making use of dual transmission frequencies;

Figure 8 is a plan view of a chart type recorder;

Figure 9 is a vertical section on line 9—9 of Figure 8;

Figure 10 is a vertical section on line 10—10 of Figure 8;

Figure 11 is a schematic and diagrammatic view of a key type printing receiver;

Figure 12 is an axial section through a wheel type indicator; and

Figure 13 is a central section thereof taken on line 13—13 of Figure 12.

The present invention includes numerous improvements on and additions to the devices of my application, Serial No. 93,740, filed July 31, 1936, for transmission systems. That application shows in greater detail than this a number of features of the actual impulse transmitting and receiving mechanisms which form no real part of the invention. It is conceivable that the impulses representing the readings of various instruments or other intelligence may be transmitted and received on any conventional apparatus. While radio transmission is preferred, obviously line wire, sub-sea, or underground cable, light beam, or any other well-known and conventional transmission means may be resorted to. For the sake of simplicity in connection with the present invention, radio transmitters and receivers have been shown merely diagrammatically, and even the apparatus for keying the transmitter and converting the energy of the receiver for the operation of the recording or indicating devices have been shown only schematically and not with the intention of providing the most desirable equipment for the purpose.

In the earlier forms of the invention it was essential to provide, on the finder dial, at the transmitter as many contacts as were provided on the instrument dial in order to be able to transmit all of the values of the instrument reading, and at the receiving end it was essential that the printing means have as many symbols as there were contacts at the finder. This made the apparatus cumbersome and complicated. In the form of apparatus shown in Figures 1 and 2 of the present drawings, a system of transmission and reception is disclosed in which the number of contacts on the finder disc is materially reduced, and sending and receiving is by means of digits disposed in the various columns, i. e., units, tens, hundreds, etc., as required. This permits the use of but twenty contacts to send numbers up to 99 and requires only the printing digits 0 to 9 at the receiver.

Referring now to the drawings, there is shown in Figure 1 at 10 the apparatus directly associated with an instrument whose readings are to be transmitted. The insulating disc 11 is provided with a contact 12 for each unit of reading of the instrument and on the shaft 13 actuated by the instrument itself is mounted a suitable arm 14 having at its outer end a brush for engaging with the various contacts 12 so that an electric circuit may be closed with the contact 12 corresponding to the instant reading of the instrument.

Associated electrically with the apparatus 10 is the finder apparatus 15 comprising an insulating disc 16 having peripherally disposed contacts in two sets, those numbered 17 corresponding to the "tens" position, and those numbered 18 to the units position of digits in a number. It is not considered necessary to show apparatus for more than two position transmission, since any further positions require mere duplications of the apparatus about to be described.

The shaft 20 is arranged to be continuously rotated at uniform speed by suitable apparatus, not shown, such as clock work, a synchronous motor, or the like, and the shaft preferably makes on the order of one revolution in from one to five minutes. This shaft carries an arm 21 arranged to successively engage the contacts 17 and 18 as the arm rotates. There are ten contacts

18 representing the units digits 0, 1 to 9, inclusive, and there are as many contacts 17 as the desired digits in the tens position. Each of these contacts 17 is connected by a suitable wire 22 to a corresponding tens position contact 23 on the instrument dial 11. These contacts 23 are spaced in a separate circle from the contacts 12 and each has the arcuate span of ten units contacts 12. These contacts 23 are likewise engaged by a brush on and electrically connected with the arm 14. The contacts 18 are connected by appropriate wires 25, each to their corresponding contacts 12. There will be as many contacts 12 representing the digit 1 as there are contacts 23, and likewise for each of the other digits of the units position. All of the wires have not been shown since they would complicate the drawings, but those corresponding to the zero contact 18 have been shown as connected to the respective zero contacts 12 on the instrument dial. In a like manner, all the other corresponding unit contacts will be connected to their respective contacts 18.

A circuit is formed from the arm 21 through wire 28, primary of transformer 29 connected to radio transmitter 30, wire 31, battery 32, wire 33, to arm 14. The circuit is completed between the two arms 14 and 21 by the proper wire 22 or 25 to provide an impulse to the transmitter. The length of this impulse is in accordance with the time it takes the arm 21 to pass over a contact 17 or 18. One contact 17 will always be connected through its wire 22 with the contact 23 on which the brush of arm 14 is resting in accordance with the instrument reading, so that the arm 21 will close the above described circuit in accordance with the tens reading; and then will pass on and close a circuit with a contact 18 in a like manner in accordance with a unit reading, so that two impulses indicating the reading of the instrument will be sent for each rotation of the arm 21.

In order that these impulses, both of the same length, may be available at the receiver for conversion into a visible or printed indication, they must have a definite time relationship to each other and to a starting point in the rotation of the arm 21. For convenience this starting point is arranged ahead of the tens and units contacts on disc 16 and is shown as a synchronizing contact 35, preferably of arcuate extent at least twice as great as that of the contacts 17 or 18. If the arm 21 rotates once per minute, it will be seen that the synchronizing contact will be engaged thereby at the beginning of each minute interval and will close a circuit through the wire 28, primary of transformer 29, wire 31, battery 32, wire 36, to the contact 35, energizing the transmitter for the sending of an impulse at least twice as long as an instrument reading impulse.

The time interval between any synchronizing impulse and the following "tens" impulse will determine the operation of the receiving apparatus for a proper showing of the "tens" position reading. Likewise, the interval between the forming of a synchronizing contact and a circuit between the arm 21 and one of the "units" contacts 18 will determine which one of these contacts is the active one caused by the position of the arm 14. At the receiving apparatus suitable equipment translates these time intervals into numerals to indicate or print the instrument reading once for each rotation of the arm 21. In this manner three impulses in timed

relation to each other serve to send any numeral from 0 to 99.

If desired, the reading of more than one instrument can be transmitted by the single finder arm 21 in the manner described in the earlier application. It will be seen that in the present drawings, the contacts 17 and 18 occupy only 180° of the periphery of the disc 16 and could be condensed into less space thereon so that the remainder of the space would be available for use for the sending of other instrument readings. The operation of such multiple instrument reading transmission is obvious.

In Figure 2 there is disclosed one form of ceiling equipment adapted for use with the transmitter of Figure 1. Here a conventional radio receiver 40 is shown connected through transformer 41 to the magnet of a suitable relay 42, which on the receipt of any impulse by the receiver draws down its armature 43 and closes a local circuit through the battery 44 and relays 45 and 46 connected in parallel. The relay 45, as shown, is a slow acting relay and is sufficiently energized to act on its armature 47 only when the impulse is as long as that sent by the synchronizing contact 35, while the relay 46 is quick acting and is energized to operate on its armature 48 by any length impulse.

As seen in Figures 2 and 3, the shaft 50 is driven from a clock work 51 or other uniform speed source of power. It is arranged to make one revolution in approximately one second less time than a revolution of the shaft 20. The shaft 50 carries a detent disc 52 having a single notch 53 in its periphery which is engaged once per revolution by the detent 54 on the opposite end of a centrally pivoted arm from the armature 47. It will be seen that on the receipt of a long synchronizing impulse, the armature 47 will be attracted, will lift the detent 54 and release the disc 52 and the shaft 50, to permit a full rotation to be effected before the detent again stops the disc and shaft and permits the arm 21 to catch up. In this way substantial synchronization between the transmitter and the receiver is effected in a simple manner so that very cheap driving mechanism can be used.

On the shaft 50 is mounted the printing or number wheel 56 which has on its periphery sets of printing characters or numbers for printing on a tape 57 moved transversely of the wheel by mechanism not shown. Printing is effected by pressing the tape down to the type on the wheel by means of a presser foot 58 carried on the end of the arm 59 supporting the armature 48. This arm is pivoted at 60 and the foot normally retained out of contact with the tape, but on the receipt of each impulse the magnet 46 causes a printing stroke of the paper against the type character which is positioned beneath it at the moment.

The particular type positioned beneath the tape is determined by the interval existing between the release of the detent disc 52 by the receipt of the synchronizing impulse and the receipt of the printing impulse.

The wheel 56 is provided with as many sets of numerals from 0 to 9 for each position to be printed as there are instruments to be recorded. For cooperation with the device of Figure 1 it is shown arranged to print two positions of digit numbers. For this purpose the "units" type 62 is arranged on the right hand side of the wheel, and the "tens" type 63 on the left side, as seen in Figure 3. The arcuate space covered by each

set of the "units" type must correspond to the arcuate space covered by the contacts 18 at the transmitter, and a like arrangement is necessary for the "tens" type. The disposition of the "units" and "tens" type on the wheel must be in accordance with the disposition of the "units" and "tens" contacts on the finder disc, and with this arrangement the receiver prints for each revolution of the type wheel a "tens" and a "units" digit exactly in accordance with the "tens" and "units" contacts engaged by the arm 14 moved by the instrument whose reading is to be transmitted.

If the instrument whose reading is to be transmitted does not fluctuate rapidly, then the transmitter and receiver shafts 20 and 50 respectively can be operated very slowly; but, if, for instance, the instrument or instruments whose readings are to be transmitted are in a free balloon, released from the ground for weather determining purposes, then obviously the temperature, humidity, and barometer readings may change rapidly and it will be desired to have faster operation of the transmitter and receiver shafts to give a continuous record at the receiver of these changing conditions as the height of the balloon is determined by observations.

The devices of Figures 1, 2, and 3 may be made to transmit numbers larger than 99 without resorting to a "hundreds" position set of contacts and printing wheel by using two digits in the "tens" position. Thus 142 would be printed 14 in the "tens" position and 2 in the "units" position.

The signal impulses including the one for synchronizing may be considered as a "code" and the disc 15 for providing the impulses a "code plate" indicative of all of the magnitudes of the conditions measured by the instruments associated therewith, while the disc 10 and its instrument may be considered as means to select the proper code from the plate to represent the existing magnitude of the condition being measured. The receiving apparatus including the synchronizing mechanism and means to convert the code to mechanical movements can be considered as the code translating means, while the printer can be designated as means to express the magnitudes.

In Figure 4 is shown, more or less schematically, apparatus for feeding tape to a tape wheel such as that of Figure 3 in which the tape can be provided with pre-printed markings indicating time intervals so that a finished tape can be studied with instrument readings shown in relation to time. For this purpose the tape must be accurately driven continuously in spite of stoppage of the printing wheel for synchronizing.

In this construction tape 57' from a roll T is moved adjacent the surface of the printing wheel or wheels 56' by means of a tape feeding roller 150, cooperating with a resilient roller 151. This feed roller is equipped with a worm wheel 152 driven from the large worm 153 fixed on shaft 50' which is driven from a suitable motor 51' by means of pinion 154 and gear 155 fixed to the shaft 50'. The printing wheel 56' is equipped with a sleeve 156 loosely journaled on the shaft 50' and having a flange 157 pressed against the hub of the gear 155 by a spring 158, thus constituting a slipping clutch which permits the wheel to be stopped by the operation of the detent on the detent disc 52' without stopping the operation of the tape.

It may be desired to print the record on the 75

tape in small type to reduce the over-all size of the apparatus and the tape, and yet to be able to read the markings as they occur without too close inspection. For instance, the tape may be 5 run behind the instrument board of an airplane to which meteorological reports are being transmitted, and in this case a light 160 in a reflector 161 can be arranged behind the tape to project the shadow of the markings on the tape onto a 10 ground glass screen 162 at the far end of a hood 163 which may all be behind the instrument board 164. With this type of apparatus, the operator is apprised of weather conditions at all 15 times and a permanent record is made of the reports received by him, so that a check on the operation of the plane can be made, and the pilot will not be able to contend that he did not receive proper reports.

In Figure 5 is shown a simple device which 20 can be applied to any of the contact arms, such as 14 or 26, to make a light contact. It is particularly suitable for the arm 14 operated by the instrument so as not to exert any undue drag on the mechanism thereof. In this figure the 25 arm 65 has a light spring 66 of spiral form secured near the end thereof so that the curved surface of the spring can be dragged over the contacts to engage them lightly, but with sufficient pressure to conduct the small amount of 30 current necessary for keying the transmitter.

In Figure 6 there is shown a mechanical arrangement for insuring the proper starting of the receiving instrument shaft only on the receipt of a long or synchronizing impulse. In 35 Figure 2 this operation is effected by the slow acting magnet 45 which does not release the detent on the receipt of a short or "reading" impulse. In Figure 6 the shaft 50' for the printing wheel carries the detent disc 52' as well as the 40 additional detent disc 68. A second shaft 69, adapted to be driven from a separate source of power such as a spring motor at a greater speed than the shaft 50', carries a detent disc 70 and a multilobed cam disc 71. A detent 72 on the 45 center-pivoted arm 73 cooperates with the single notch in disc 68 and is released only by the operation of one of the cam lobes 74 on the disc 71.

The discs 52' and 70 have peripheral notches 50 under the control respective of detents 75 and 76 on arms jointly movable by the striker 77 on the end of an arm actuated by the armature 78 of magnet 79. The local circuit of this magnet is closed by relay 80 operated through the 55 former 41' from the radio receiver. On the receipt of an impulse of short duration the magnet 79 is energized, draws down its armature 78, causing the striker 77 to release both detents 75 and 76. Shaft 69 then begins to rotate, but 60 shaft 50' is retained stationary by detent 72. The short impulse ceases and the detent 75 is returned to its notch before the cam lobe 74 is effective to release detent 72, so that synchronizing is not improperly effected in the event that 65 the receiver is tuned-in after a synchronizing impulse is sent but before an instrument reading impulse is sent.

When a long impulse is received, however, the magnet 79 is retained energized long enough for 70 the detent 72 to be released by a cam lobe 74 so that the shaft 50' is then free to rotate for a full revolution since there are only single notches in discs 52' and 68. The number of lobes of the disc 71 is not important, but it is 75 preferred that there be the same number as

notches in the periphery of disc 70 so that shaft 69 is stopped as soon as possible after having performed its function.

In Figure 7 there is disclosed an alternative form of transmitting equipment which makes use of a radio transmitter 85 capable of sending signals at two different carrier frequencies, each frequency adapted to be keyed by its respective transformer 86, 87. In this arrangement the instrument dial is the same as that described in 10 connection with Figure 1, and while the finder dial may be the same, it has been shown as slightly different having the "tens" contacts 17² on an arc of different radius than the "units" contacts 18² and having two arms 88 and 89 for 15 contacting with them respectively. These arms are spaced angularly at least the distance of the arcuate extent of the "tens" contacts. The first frequency of the transmitter, that controlled by the transformer 86, is used solely for the sending 20 of the synchronizing impulse, and for this purpose is connected by wires 90 and 91 through the local battery, the arm 88, and the synchronizing contact 92. The other frequency is used for sending the various impulses corresponding 25 to the digit positions for the instrument readings.

For use with this transmitter, a double frequency receiver is necessary, one frequency operating a magnet for releasing the printing wheel 30 for synchronizing purposes, and the other a magnet for giving the printing impulse to the tape. The operation will be obvious from the description of the receiver for use in connection with the transmitter of Figure 1. The only difference will 35 be that the magnets 45 and 46 of Figure 2 will be operated from the two frequencies of the receiver rather than in accordance with the lengths of the impulses.

It may be preferred under certain conditions to 40 chart a curve of the readings of one or more instruments rather than to print a tape in figures or to otherwise indicate or record, and for this purpose, receiving equipment embodying the mechanism of Figures 8, 9, and 10 may be re- 45 sorted to. Here the record is dotted on a paper chart or disc 100 which is rotated slowly about its center 101 by any suitable clockwork mechanism. Such charts may be timed to rotate once in twenty-four hours, seven days, or any other desired interval. With accurate timing of the drive mechanism, the chart may have indications of hours and minutes or the like thereon in the form of lines 102 concentric with the pivotal axis 103 of the pen arm 104 carrying at its outer end 50 a suitable marking device.

This pen arm is movable over the chart under the action of a cam 105, the shape of which may be varied to suit circumstances, that shown being symmetrical about a longitudinal axis and 60 providing movement outward for the operating stroke of the pen during 180° of revolution of the cam. The other 180° may merely return the pen or may be used for other recording as desired. The pen arm is equipped with a roller 65 cam-follower 105' held against the cam at all times by a helical spring 105'. The cam 105 is secured to the shaft 106 driven through the gear 107 by any suitable clock-work mechanism adapted to synchronize or substantially synchronize the 70 rotation of the shaft with the rotation of the finder arm on the transmitter. This transmitter is preferably of the type disclosed in my earlier application and not of the digit position type.

The shaft 106 is equipped with a detent disc 75

108 having a single notch in its periphery to be engaged by the detent 109 and stopped once per revolution for synchronizing purposes in exactly the same manner as described in connection with 5 the printing recorder of Figure 2. This detent is released upon energization of the slow acting magnet 110 upon the receipt of a long synchronizing impulse.

The pivot 103 for the pen arm is a shaft both 10 rotatably and slidably fitted in a sleeve 111 in the adjustable portion of the frame 112 of the mechanism and is supported by the coil spring 113 in such a manner as to hold the marking tip of the pen above the paper of the chart. The 15 armature 114 on the lower end of this shaft 103 is attracted by the magnet 115 on the receipt of each instrument reading impulse to draw the pen into marking engagement with the paper, forming a dot. The series of dots from successive 20 sweeps of the pen arm dot a curve recording the successive readings of the instrument. Of course, the chart is previously calibrated in concentric circles for the particular instrument so that the values of points on the chart can be read 25 at will.

The slow-acting and pen depressing magnets are connected for operation from the output of a conventional radio set in a manner already described. The succession of synchronizing 30 pulses, preferably occurring when the pen is near the center of the chart, will result in the drawing of a dotted circle on the chart which can be used as a reference point, if desired, in studying the curve of instrument readings. The adjustable portion 112 of the frame 112 is manually 35 rotatable to set the zero position of the pen arm.

In Figure 11 is shown an extremely simple printing recorder for use with the multi-position digit transmitter of Figure 1. It is shown largely 40 schematically and intended for connection to the output of a conventional radio receiver or other similar device. The keys 120 numbered respectively 0 to 9 represent the keys of mechanism of the typewriter style, and each is provided with 45 a magnet 121 so associated therewith that upon energization, the key is drawn down to operate a type number corresponding to the key number to print on a tape or sheet as desired. One additional key 122 is provided for spacing and is 50 under the control of a magnet 123.

A shaft 124 is adapted to be driven and synchronized with the transmitter in the manner already described as by means of the detent disc 125, detent 126, and magnet 127. This is preferably a slow acting magnet. This shaft 124 drives an arm 128 which passes over a series of contacts mounted on the insulating disc 129. The first group of these contacts numbered 0, 10, 20, 30, 40, 50, correspond in number and position 60 to the "tens" position contacts on the finder disc at the transmitter, and the second group of contacts numbered 0 to 9, inclusive, correspond in number and position to the "units" contacts on the finder at the transmitter. The zero contact 65 of the "tens" group is connected to the zero contact of the "units" group and the two, by means of wire 130, are connected to one terminal of the magnet 121 of the zero key. Likewise, the "tens" contact representing 10 is connected to the 70 "units" contact representing 1 and to the magnet of the key bearing the number 1, and so on through the whole set so that when the hand closes the circuit about to be described, a single "tens" number is printed on the tape or sheet 75 which is then spaced, as in a typewriter, to re-

ceive the second or "units" number, whereby an instrument reading is recorded.

The second terminal of each of the magnets 121 is connected by a common busbar 131 to a local battery 132 through the contacts of a relay 133 to the arm 128 by way of wire 134. Relay 133 is operated through the transformer 135 from the receiving set and is energized every time an impulse is received. If, at the time of the receipt of such an impulse, the arm 128 is on the contact numbered 10, then a circuit is closed through a corresponding magnet 121 and a "1" is printed. If then a second impulse is received when the arm 128 engages the contact numbered 3, then a "3" is printed showing a total of 13 as the instrument reading. After this reading, it is desirable to provide a space prior to the next reading which may be from the same or another instrument, as previously described, and this spacing is alternatively accomplished once per revolution, or once after the reading allocated to each instrument, by means of a contact 136 engaged by the arm 128 and directly closing through the local battery 137 the circuit to the magnet 123. The synchronizing magnet 127 is connected in circuit with the relay 133 and local battery 132 to operate in a manner already described. The synchronizing impulse has no effect in printing, since at the time it is given no contact to a printing magnet circuit is made by the arm 128, although if desired, this arm could rest on a contact which would print a key to indicate the time, the nature of the indication, the location of the sender, or some other desired information. Likewise, where several instruments are recorded, there may be given, prior to or after the recording for each, a printed letter to show which type of record is being made.

The apparatus of Figures 2 and 11 may be arranged in conjunction with that of Figure 1 to indicate the source of the reading signals. For instance, an airplane may get weather reports from different stations. Each station can have a number or symbol arranged at its transmitter at a definite and different angular position on the finder disc to operate the receiver to print this symbol once per revolution of the finder. Thus each reading may be preceded or succeeded by a number representing the sending station; thus 9 46 when 9 is the station and 46 the reading.

Figures 12 and 13 illustrate a portion of a receiving apparatus intended solely to provide indications for visual observation of the reading of an instrument as transmitted by, for instance, the apparatus of Figure 1 or 7. The whole indicating apparatus is shown as enclosed in a substantially cylindrical housing 175. Suitably mounted therein for rotation are a pair of number wheels 176 and 177 having the peripheral cylindrical flanges 178 each carrying a plurality of groups of numbers thereon from 0 to 9. The numbers are consecutively arranged on each flange and there are as many groups thereon as clutch detents later to be described, the groups being spaced circumferentially from each other and in equal number on the two wheels. A suitable window 179 is provided in the housing for observing the single number on each wheel which is placed opposite the window by the mechanism so that the reading of an instrument transmitted to the apparatus can be taken.

The two cup-shaped wheels are spaced apart as shown and concentrically mounted for rotation within the space between them is the clutch 75

wheel 180 composed of a pair of discs spaced apart and appropriately joined by members 181. This wheel carries on the inner face of each disc a clutch arm 182 pivoted intermediate its ends to ears 183 struck up from the corresponding disc. The outer ends of the arms are arranged, for instance, as at 184 to engage notches or other similar means 185 on the inner faces of the corresponding number wheels. There are as many of these notches on the inner face of each wheel as there are groups of numbers on its outer flange.

A sleeve 186 extends from the left hand disc of wheel 180 out through appropriate bearings and mounts the gear 187, rotated by the pinion 188 driven from the motor 189. This motor is of the type described in connection with previous figures and is adapted to rotate the clutch wheel at approximately the same speed as the finder arm at the transmitter. A detent disc 190 is mounted on the sleeve 186 and synchronizes the operation of the clutch wheel with the finder by means of the detent 191 and its associated magnet 192 which releases the detent for synchronizing purposes on the receipt of a synchronizing impulse as previously explained.

The number wheels are equipped with suitable braking means, not shown, to hold them in whatever position they may be placed in spite of rotation of the clutch wheel hollow shafts without in their bearings.

Normally, the wheels are stopped with the zero of the "tens" wheel and the beginning of a blank space on the "units" wheel opposite the window. With the clutch wheel positioned with the detent 191 in its single notch, the clutch fingers 184 take into the notches 185 which are positioned properly for that purpose. When the synchronizing impulse is received, the clutch wheel begins to rotate and the number of wheels are drawn along with it by the action of the clutch fingers held into the notches by the spring 193. On the receipt of the impulse for the "tens" position indicated by wheel 177, its clutch arm is withdrawn from the corresponding notch by the action of a stationary magnet 194 operating on its armature and moving the rod 195 loosely mounted in sleeve 186 and pivotally secured at 196 to the opposite end of the corresponding clutch arm. The wheel is thus deprived of its driving force and stops with that number on its face opposite the window which corresponds to the "tens" number contact engaged by the finder arm. A like operation takes place then in connection with the "units" wheel which is permitted to stop in the proper position to represent the "units" number necessary for the proper indication of the instrument reading.

In each case the number positioned adjacent the window is dependent on the time interval elapsing between the synchronizing impulse and the impulse necessary to operate either the magnet 194 or the magnet 197 to release the proper clutch arm. It will be necessary to provide blank spaces on the wheel flanges so that the movement of the "units" wheel, which starts at the same time as the "tens" wheel will not bring any figures thereon in position until the "tens" wheel has had an opportunity of moving as far as the 9 thereon, if necessary. Thereafter, movement imparted to the "units" wheel brings its numbers into position for stoppage as required.

In order that the clutch arms 182 do not reengage the wheels at the next notch 185, shown spaced only 90° from the first one, and again start moving the number wheels, a shield 198 is pro-

vided for each wheel, the two of them being supported from an arm 199 passing between the flanges and secured to the inside of the casing. Each of these shields is slightly more than 180° in arcuate extent, whereby 90° of rotation is permitted for the operation of both the "tens" and the "units" wheel by providing four notches 185. Appropriate adjustments permit a larger or smaller number of notches to be used. The clutch arms riding up on the surface of these shields are thus prevented from engaging any notches during 180° of rotation. This assures that the numerals appearing before the window are available for at least a period of one-half revolution of the clutch wheel. When the clutch arms drop off of the shields, the ensuing notches to be engaged by them will be positioned from the last ends of the shields a distance equal to the movement imparted to the corresponding wheel before the clutch arm was released by its magnet, as will be clear from an inspection of Figure 13. The distance necessary to move the wheel back to zero is then the difference between that first moved and 90°, and this amount of movement will now be imparted to the wheel when the clutch reengages a notch. When this notch is brought back to the starting point, the wheels are reset to receive the next movement transmitted to them and the whole operation is repeated.

In order to use this form of receiver with the transmitter of Figure 1, a selector somewhat like that shown in connection with Figure 11 is necessary to select the magnets 194 and 197 to operate with the "tens" or "units" impulse. This selector can be extremely simple, having only two contacts thereon, one for the "tens" of arcuate extent equal to that of the tens contacts on the finder, and a similar one for the units.

The device is particularly adaptable for use with a multi-frequency transmitter, such as shown in Figure 7, where one frequency can be used for "tens" and another for units, and synchronizing can be effected by an additional frequency or by either one of the two frequencies by the use of a slow acting relay.

The device shown is arranged to operate with only two number wheels, but obviously could be extended to any desired number of wheels in a manner which need not be described since it would comprise a simple duplication of parts. A larger number of clutch notches and hence a greater number of groups of figures on each wheel will insure a longer "reading" period for each number and a shorter period in transit, and may be desirable.

Having thus described the invention, what is claimed as new and desired to be secured by Letters Patent is:

1. Apparatus for repeating instrument readings at a distance comprising a transmitter, a receiver and a conventional channel therebetween, a measuring instrument at the transmitter adapted to indicate a plurality of digits, a single rotary finder at the transmitter operable to periodically find the plural digit reading of said instrument, a single rotary device at the receiver, means to maintain said finder and rotary device in substantial synchronism including the sending of a synchronizing signal once per finder revolution, said finder being arranged to cause said transmitter to send one impulse per revolution for each digit in the instrument reading spaced in relation to the synchronizing signal to represent the position and magnitude of the digit and means

at the receiver actuated by said rotary device on receipt of each impulse to indicate the corresponding digit in its proper position.

2. Apparatus for repeating instrument readings at a distance comprising a transmitter, a receiver and a conventional channel therebetween, a measuring instrument at the transmitter adapted to indicate a plurality of digits, a single rotary finder at the transmitter operable to periodically 5 find the plural digit reading of said instrument, a single rotary device at the receiver, means to maintain said finder and rotary device in substantial synchronism including the sending of a synchronizing signal once per finder revolution, 10 said finder being arranged to cause said transmitter to send one impulse per revolution for each digit in the instrument reading spaced in relation to the synchronizing signal to represent the position and magnitude of the digit and means at 15 the receiver actuated by said rotary device on receipt of each impulse to print the corresponding digit in its proper position.

3. Apparatus for duplicating the reading of an instrument of the single dial and pointer type at 20 remote points comprising a transmitter, receiver and conventional channel between them, said transmitter including means to periodically resolve the single point instrument reading into transmitted signal impulses one for at least each 25 of two digits therein, each impulse representative 30 of the position and magnitude of its corresponding digit, said means sending a single synchronizing impulse at the beginning of each period from which the said signal impulses are arbitrarily spaced and means at the receiver to translate said arbitrary spacing into indications 35 corresponding in position and value to said instrument reading.

4. Apparatus for duplicating the reading of an instrument of the single dial and pointer type at 40 remote points comprising a transmitter, receiver and conventional channel between them, said transmitter including means to periodically resolve the single point instrument reading into transmitted signal impulses one for at least each 45 of two digits therein, each impulse representative of the position and magnitude of its corresponding digit, said means sending a single synchronizing impulse at the beginning of each period from which the said signal impulses are 50 arbitrarily spaced and means at the receiver to translate said arbitrary spacing into printed digits corresponding in position and value to said instrument reading.

5. A transmitter for sending over a conventional channel the reading of an instrument of the single dial and pointer type comprising in combination, means to periodically resolve the single point instrument reading into transmitted signal impulses, one for at least each of two digits 55 therein, each impulse representative of the column position and magnitude of its corresponding digit, means to send a single synchronizing impulse at the beginning of each period, said first 60 means spacing said signal impulses in column sequence from said synchronizing impulse in predetermined amounts representative of their digit magnitude.

6. Apparatus for transmitting the readings of 65 a single digit and pointer instrument to a distance, comprising in combination, a code plate having a single contact for each figure in each column position of any such reading to represent all of the measured magnitudes thereof, means 70 associating said instrument with said plate to

energize one contact of each column position to code the instant reading of the instrument, and a brush movable to periodically engage each contact to transmit said code.

7. Apparatus for repeating instrument readings at a distance comprising a transmitter, a receiver and a conventional channel therebetween, a measuring instrument at the transmitter adapted to indicate a plurality of digits, a single rotary finder at the transmitter operable to periodically find the plural digit reading of 10 said instrument, a single rotary device at the receiver, means to maintain said finder and rotary device in substantial synchronism including the sending of a synchronizing signal once 15 per finder revolution, said finder being arranged to cause said transmitter to send one impulse per revolution for each digit in the instrument reading spaced in relation to the synchronizing signal to represent the position and magnitude 20 of the digit, a type wheel mounted for movement in unison with said rotary device, said wheel having a group of characters from 0 to 9 for each digit position to be sent, each group being spaced longitudinally on the wheel from the 25 next group and circumferentially in advance thereof and means actuated by the receipt of any impulse to cause said wheel to print the digit then in printing position.

8. Receiver mechanism for printing records of 30 multiple digit instrument readings transmitted as one impulse per digit each differently spaced in relation to a synchronizing impulse, comprising a rotary member, means to synchronize the same with the impulse sender, a printing key for 35 each figure required, a magnet for operating each key, a contact for each magnet for each digit position, the contacts for each position being sequentially arranged to follow those of the next higher position, a brush movable in unison with 40 said rotary member to engage said contacts serially to form a local circuit from a source of power to the magnet connected to the engaged contact and means actuated on receipt of an impulse to close the local circuit then formed by the brush 45 to print the corresponding key.

9. Synchronizing mechanism for a transmitter and receiver connected by a conventional channel comprising a contactor at the transmitter driven at substantially constant rotary speed, means to close a circuit thereby once per revolution to send 50 a synchronizing impulse over said channel, a rotary device at the receiver adapted to be driven at substantially the same speed as said contactor, a detent to stop and hold said device once per revolution, means actuated by said synchronizing impulse to release said detent, means at the transmitter to send at least one additional or signal impulse of shorter duration per contactor revolution, said detent releasing means in the 60 receiver responding only to the longer impulses.

10. Phasing and synchronizing mechanism for instrument reading transmission systems, including a rotary finder and a rotary indicator, in combination, means to drive said finder at substantially constant speed, means tending to drive said indicator at substantially the same speed, detent mechanism biased to stop the indicator once per revolution, a long synchronizing impulse initiated once per revolution by said finder, 70 a short reading impulse initiated once per revolution by said finder at an interval subsequent to the synchronizing impulse representative of the magnitude of the reading, slow acting magnet cooperating with the detent to release the same, 75

said magnet acting only on receipt of said long impulses.

11. Receiver mechanism for repeatedly printing records of multiple digit instrument readings transmitted as one impulse per digit, each spaced in spaced relation to a single synchronizing impulse so as to determine its column position and magnitude, comprising in combination, a clock-work, a record tape, means actuated by said 5 clockwork to drive said tape past a printing position, a printing wheel rotatable transversely of said tape and slightly spaced therefrom at a printing position, means driving said wheel from said clockwork, means to stop and hold said wheel 10 against rotation once per revolution, said means being rendered ineffective on the receipt of a synchronizing impulse, a set of printing members on said wheel for each column to be printed, said sets being in laterally spaced positions on the 15 periphery of the wheel and also in staggered relation circumferentially and means to cause printing cooperation of the tape and nearest printing digit on receipt of each instrument reading impulse.

12. Receiver mechanism for printing records of multiple digit instrument readings transmitted as one impulse per digit, each differently spaced in relation to the same synchronizing impulse, comprising a rotary member, means to synchronize the same with the impulse sender, a printing key for each figure required, a magnet for operating each key, a contact for each magnet for each digit position, the contacts for each position being sequentially arranged to follow those of the 10 next higher position for engagement by a brush carried by said rotary member to form a local circuit through its magnet and a source of current, means actuated on receipt of an impulse to close the local circuit then formed by the 15 brush to print the corresponding key, a magnet-actuated spacer key to move the paper on which the keys print, and a contact closed once per revolution of said rotary member to deliver current to the spacer key magnet. 20
